SUPPORT FOR AIR CONDITIONER UNIT

Eric P. Cahn, Brooklyn, N.Y.

Application March 27, 1957, Serial No. 648,874

8 Claims. (Cl. 312—213)

This invention relates to an improvement in a support or enclosure for a built-in, wall-type air conditioner.

Heretofore air conditioner units which have been built into the exterior walls of buildings have each been provided with a base pan which is an integral part of the frame of the air conditioner unit. Building walls in which these units are mounted are provided with rectangular openings each of which has a base plate or platform to receive and support the unit. In addition the opening may be framed with a metal sleeve in which the unit is enclosed at the top and sides. Thus the conventional installation of such an air conditioner unit includes one frame for the building wall opening and an additional frame and base pan for the unit. Such prior known base pans have failed to provide for complete drainage of water received from the unit. Thus the cooling efficiency of the unit was reduced. Excess water was directed into the room where the unit was located. The walls of the room and building were stained and damaged by this water, and the working parts of the unit were rusted and corroded by the excess water.

According to the present invention, these difficulties are avoided by providing a base pan which may be cast, molded, or otherwise formed of cement, concrete, plastic, metal, or other suitable material. This pan may be formed for flush mounting and installation in an opening in a building wall. Alternatively it may be formed in situ in the opening of the building wall by known concrete or cement casting methods. The material of which the pan is made must be rugged, corrosion resistant, fire proof, and meet municipal building code standards for exterior building wall structural materials.

The base pan according to the invention extends from the exterior face of the building wall to the interior of the building. The pan has a sloping bottom with the front end lowermost. At the front end are a plurality of drain holes. Thus moisture which condenses on the unit and flows into the pan can drain out of these drain or "weep" holes. The drainage of excess water prevents objectionable corrosion of the unit and staining of building walls. The drain holes may be provided with bronze, brass, copper, or aluminum tubing inserts to protrude from the front of the pan. The inserts may be formed with nozzle ends to disperse water therefrom in a fine spray. Included in the pan are channels, rails, grooves, ridges, or other guide means to facilitate installing an air conditioner unit thereon. A plurality of ledges, pads or other projecting elements may be provided in the pan to support a U-shaped sleeve enclosure for the air conditioner unit. The pan also has support elements at the front for a louvered plate or panel. The pan may be provided with a well for containing coolant water which is cast on the air conditioner unit by a slinger fan.

During the course of construction the pan may be built into an opening in a building wall. A louvered panel may be used to cover the opening until it is desired to install an air conditioner unit therein. The U-shaped sleeve may be installed at the same time the pan is in-

2

stalled or it may be later added. The air conditioner unit can then be easily installed in the waiting sleeve on the pan. The louvered panel will then serve as the outer cover of the unit. Such a type of installation considerably reduces the cost of the air conditioner unit installation, and economizes in labor for installation and maintenance. The invention makes it possible to reduce the cost of air conditioner installations by employing units which have no exterior inclosure sleeve and base pan, since the features are provided in the support and enclosure with which the present invention is concerned.

It is therefore a principal object of the invention to provide a support and enclosure for an air conditioner unit in an exterior building wall installation including a pan adapted to receive and drain excess water from the unit.

It is a further object to provide a base pan for supporting an air conditioner unit, the pan being cast or molded of cement, concrete, or the like.

It is a further object to provide a base pan and U-shaped sleeve for supporting and enclosing an air conditioner unit in an opening in a building wall.

It is a further object to provide a base pan for an air conditioner unit, the pan being arranged to drain all excess water collected therein from the unit to increase the B.t.u. calorific cooling efficiency of the unit.

Other and further objects and advantages of the invention will become apparent from the following detailed description taken together with drawing, wherein:

Fig. 1 is a top plan view of a pan embodying the invention.

Fig. 2 is a cross sectional view taken on lines 2—2 of Fig. 1, from front to rear of the pan, and showing a portion of the exterior building wall.

Fig. 3 is another cross sectional view taken on lines 3—3 of Fig. 1, from side to side of the pan, with building wall portions omitted.

Fig. 4 is a sectional view of a portion of the front of the pan taken on lines 4—4 of Fig. 1, and including a condensate discharge tube.

Fig. 5 is a view similar to Fig. 4 showing a condensate discharge tube of another form.

Fig. 6 is a top plan view of the portion of the pan and discharge tube shown in Fig. 5.

Figs. 7 and 8 are perspective views of portions of guide rails which may be used in the pan.

Fig. 9 is a perspective view of a pan and sleeve installed in a building wall during course of construction thereof.

Fig. 10 is a perspective view of a reinforcement member which may be installed in the pan of Fig. 9.

Fig. 11 is a sectional view of the pan alone, taken on lines 11—11 of Fig. 9.

Fig. 12 is a front elevational view of a pan and louvered panel installed in a building wall opening.

Fig. 13 shows a section of a louvered panel.

The form of pan 20 shown in Figs. 1 to 4 is a shallow rectangular member having a front wall 21, a rear wall 22, sides 23, 24 and a rectangular bottom 25. The pan is formed of cement or concrete or may be plastic or some composition material. The upper surface of bottom 25 slopes downwardly from rear to front as clearly shown in Fig. 2. The top edge of rear wall 22 should be above the floor level F of the room in which the pan terminates. If desired this rear wall 22 may be concealed by a facing 27 of plaster, wood, or other suitable material. The pan is installed in an opening formed in the building wall 28. This wall is shown made of bricks but it could be solid concrete masonry or any other suitable construction conventional to exterior building walls. The front wall 21 may be painted to harmonize with the exposed face of the wall 28. In the bottom 25 are two or

more grooves 30. These grooves are formed when the pan is initially molded or cast. They may be lined with rail inserts 32 of metal, plastic, etc. These grooves and inserts extend below the upper surface of the bottom 25 to leave the bottom free of obstructions and to serve as guide means to facilitate installation of an air conditioner unit U thereon. The grooved structure securely retains the unit, indicated by dotted lines in Fig. 2. At the sides 23 and 24 on the bottom 25 are blocks or pads 33 which serve to secure and support a metal sleeve or frame for the unit. The pads have coplanar horizontal top surfaces which may be provided with threaded holes 34 or may have threaded metal inserts. At the top of wall 21 in the interior of the pan are disposed lugs or clips 35 in which a front panel may be supported. The lugs are formed as hollow box-like projections on wall 21.

Wall 21 is formed with a plurality of openings 36 at the bottom thereof so that water condensate may drain out of the pan. The forward and downward slope of bottom 25 insures that all excess water collecting in the pan will drain out of the openings. Short pipes or tubes 37 of non-corrosive material may be inserted in openings 36 so that the draining water does not drop on the outer face of the building wall. The tubes 37 may be formed with flattened nozzle ends 38 as best shown in Fig. 5 and to serve as means for dispersing the water in fine sprays.

In Fig. 7 is shown a portion of a grooved rail or channel which may be inserted in a groove 30. This rail has a tapered groove 40 which is wider at the top than the bottom. This groove may also have straight sides; or the rail may have over-hanging portions 41 as shown in Fig. 8. In the structure of Fig. 8, the over-hanging wall portions effectively grip the mounting feet (not shown) of an air conditioner unit to be installed thereon.

A cavity or well 42 may be formed in the bottom 25 of the pan. This well will be located beneath the fan blades B of the air conditioner unit to be installed on the pan. The fan blades serve to direct a spray of coolant water from the wall onto the condenser of the air conditioner unit.

In Figs. 9 to 11 is shown a metal pan 20'. This pan may be preformed and then installed in wall 28. Pan 20' which is preferably of molded or cast construction may be formed on the building wall during construction thereof. Pan 20' however will be prefabricated and then installed in the wall. The pan may be formed with a flat bottom 25 and include the cavity or well 42 for the "slinger fan" blades B. Blocks 33 are provided in the pan to support the sleeve 45. This sleeve includes two vertical plates or partitions 46 having ledges 47 with slots 48. A plate 49 is mounted on partitions 46 and secured by bolts 50. The slots 51 in plate 49 and slots 48 in the ledges 47 permit a certain amount of lateral adjustability to accommodate the sleeve to various widths of pan 20'. The partitions 46 have inturned flanges 52 with apertures for securing the partitions to blocks 33 by means of bolts 53. Clips 35' on front wall 21 are flexible members which serve to support a louvered panel. Plate 49 has a depending flange 61 which fits over the top of panel 55 as shown in Fig. 13. Screws 76 secure the panel to the flange. Louvers 60 are supported in frame 60' of panel 55. The bottom of the panel rests in clips 35 or 35'. If desired the plate 49 may be formed of a refractory material such as mica-asbestos, asbestos, vermiculite which is extended downward at the front of the enclosure to form the closed upper portion 59 of panel as shown in Fig. 12. The framed louvered portion 60' of the panel may be separately formed from the upper portion 59 or it may be integrally formed therewith in the same molding or casting operation.

A rectangular plate 56 may be provided to strengthen the pan and support the air conditioner unit. This plate as shown in Figs. 9 and 10 may have ridges or ribs 57 which serve as guide rails and support elements as well as guides

for installing the unit. The plate may have a rectangular aperture 58 which registers with the top opening in well 48.

The sleeve 45 is generally U-shaped member and may have adjustably positionable side plate 46 disposed on pads or blocks 33 of either pan 20 or pan 20'. Alternatively the side plates 46 may have V-shaped or dove-tailed ends 73, 74 which are fitted in V-grooves or dove-tailed grooves 72, 75 of the top plate 49 and pan 20" as shown in Fig. 12. The side plates 46 as well as pan 20" may be formed of the same mica-asbestos, vermiculite or other refractory material as the top plate 49.

The outward appearance of the pan whether of the form 20, 20' or 20" will be as shown in Fig. 12 with only the front of wall 21 and tubes 37 exposed. This face of wall 21 may be painted or otherwise finished to harmonize and blend with wall 28. It can be covered with a suitable cover if desired. The front wall 21 is flush with the outer side of wall 28 and the rear wall is flush with the inner side of the wall 28, so that the pan is wholly contained in the opening in the wall as clearly shown in Figs. 2 and 12. The pan is secured by mortar which also secures the adjacent bricks in the wall.

The slope of the bottom of the pan insures that no water which condenses on the condenser of the air conditioner unit is discharged into the adjoining room or remains to corrode the unit or stain the building walls.

The top of the rear wall 22 is located above the level F of the floor of the room, so that the floor remains dry. The water which collects in well 42 may serve as a coolant which the fan blades B will direct against the condenser of the air conditioner unit U. The discharge tubes 37 will insure that excess water cannot collect in the pan while the well 42 has its bottom below the lowest level of the remainder of the pan so that sufficient coolant water can collect in the well. Since the pan is arranged to drain all excess water received from the unit, the B.t.u. calorific rating of cooling and the thermodynamic efficiency of the unit is increased to a remarkable degree.

Sleeve 45 consisting of the plates 46, 49 together with the louvered panel 55 constitute a cover for the air conditioner unit which replaces the usual frame and cover now provided for such units. The plates 46, 49 and panel 55 can be cast in one piece as an integral unit or may be made as several members joined together to form a unit.

What is claimed and sought to be protected by Letters Patent of the United States is:

1. A support for flush mounting of an air conditioner unit in a wall of a building, comprising a rectangular pan having flat upstanding side walls, a front wall, a rear wall and a flat, imperforate rectangular bottom integrally joining said side, front and rear walls for collecting water dripping from said unit, the length of the pan between front and rear walls thereof being substantially equal to the thickness of the building wall so that the pan may be flush mounted at front and rear walls thereof in an opening in the building wall, said bottom having an upper surface formed with a downward slope from the rear wall to the front wall, said front wall having a plurality of spaced openings at the lowermost end thereof adjacent said bottom and a drain tube disposed in each of the openings and extending outwardly from said front wall for draining and dispersing water collecting in the pan, said bottom being formed with a pair of straight grooves extending parallel to said side walls and extending below the level of said upper surface so that said bottom is clear of obstructions between said grooves, said bottom being formed with a well near said front wall for collecting coolant water for said unit.

2. A support for an air conditioner unit according to claim 1, wherein each of said tubes is formed with a nozzle at its free end for dispersing water therefrom in a fine spray.

3. A support for an air conditioner unit according to

claim 1, further comprising apertured block members disposed on said bottom at said sides for supporting a frame enclosure for said unit, and clip means carried on said front wall for removably carrying a louvered front panel for said unit.

4. A support for an air conditioner unit according to claim 1, wherein each of said grooves is lined with a channel insert to receive and retain mounting feet of the air conditioner unit.

5. A support for an air conditioner unit according to claim 1, further comprising a pair of upstanding side plates having lower ends secured to the sides of the pan, and a top plate secured to upper ends of said side plates above said pan.

6. A support for an air conditioner unit according to claim 1, further comprising a pair of laterally disposed side plates, supported on the sides of the pan, a top plate supported on said side plates, and a louvered front plate covering a front opening defined by said side plates, pan, and top plate, said front plate, side plates and top plate being integrally jointed to form a cover for said air conditioner unit.

7. A support for an air conditioner unit according to

claim 1 wherein said pan is formed of molded cementitious material.

5 8. A support for an air conditioner unit according to claim 5, wherein said pan and top plate are formed of cementitious material adapted for permanent bonding by mortar in said building wall.
